[57] CLAIM

The ornamental design for an aft double deck airplane, as shown and described.

DESCRIPTION

FIG. 1 is a perspective view of an aft double deck airplane showing our new design;

FIG. 2 is a left side elevational view thereof, its right side, not shown, being the mirror image of this left side;

FIG. 3 is a top, plan view thereof;

FIG. 4 is a front elevational view thereof;

FIG. 5 is a bottom, plan view thereof; and,

FIG. 6 is a rear elevational view thereof.

Fig. 1
